DESIGN FOR A DESK

Herman E. De Vries, New York, N. Y., assignor to H. T. Cushman Mfg. Co., North Bennington, Vt.

Application June 27, 1936, Serial No. 63,547

Term of patent 3½ years

To all whom it may concern:

Be it known that I, Herman E. De Vries, a citizen of the United States, residing at New York city, in the county and State of New York, have invented a new, original, and ornamental Design for a Desk, of which the following is a specification, reference being had to the accompanying drawing, forming part thereof.

I claim:

The ornamental design for a desk substantially as shown.

HERMAN E. DE VRIES.
